UNITED STATES PATENT OFFICE.

MAX E. BIERACH, OF MILWAUKEE, WISCONSIN.

STAMPING-MACHINE.

SPECIFICATION forming part of Letters Patent No. 632,548, dated September 5, 1899.

Application filed February 3, 1899. Serial No. 704,370. (No model.)

To all whom it may concern:

Be it known that I, MAX E. BIERACH, a citizen of the United States, residing at Milwaukee, in the county of Milwaukee and State 5 of Wisconsin, have invented new and useful Improvements in Stamping-Machines, of which the following is a specification.

My invention relates to improvements in stamping-machines, and pertains especially to 10 that class of stamping-machines illustrated in connection with my former application, Serial No. 662,170, filed December 16, 1897, for machines for making antitacks.

The object of my invention is to provide 15 means for stamping or printing labels, with especial reference to that class of labels which are stamped or printed upon metal or other rigid surfaces.

In the following description reference is had 20 to the accompanying drawings, in which—
Figure 1 is a front view of my invention. Fig. 2 is a top view of the same. Fig. 3 is a sectional view drawn on line $x-x$ of Fig. 1. Fig. 4 is a sectional view drawn on line $y-y$ 25 of Fig. 1. Fig. 5 is an enlarged detail view drawn on line $U-U$ of Fig. 1. Fig. 6 is a rear view with the inking-pad and other parts removed to show the interior construction of the vertical reciprocating printing-head, and 30 Fig. 7 is an enlarged detail view drawn on line $T-T$ of Fig. 6.

Like parts are identified by the same reference-letters throughout the several views.

A bed-plate A is reciprocated horizontally 35 underneath a vertically-reciprocating printing-head B, the latter being actuated from the source of power by means of the belt C, pulley C', eccentric D, adjustable connecting-link d, and lever E. The motion of the printing-head is communicated to the bed-plate through the springs F, rack-bars F', pinions f, shafts f', gear-wheels G, and horizontal rack-bars G'. The printing-head is supported between and guided by the vertical posts H, and 40 the die or printing plate I is supported underneath the head by means of rods I', which extend upwardly through guide-apertures in the head, to which they are secured by means of spring-buffers J. The object of the springs 45 J is to permit sufficient downward pressure to affix the stamp and at the same time relieve the strain which would be experienced

if the printing-die were secured rigidly to the head.

In order to supply the ink to the die or 55 printing plate I, I have provided an inking-roller K, which is actuated from the head B by means of the ears L, links L', ears M, cross-head M', lever N, and roller-supporting forked arm N'. The cross-head M' is supported upon 60 a rod O, which connects the supporting-posts H and forms a fulcrum for the lever N. The forked arm N' is secured to the lever N by a hinged joint P and by a connecting-spring Q, so that the inking-roller K will pass yield- 65 ingly under the stamping-die I, one edge of which is curved upwardly so as to receive the inking-roller on its under side.

R is an inking-pad supported from the posts H by the arms S, cross-bar T, and spring- 70 cushion U.

It will be observed that as the printing-head B is moved upwardly its motion will be communicated through the connecting-links, cross-head, lever N, and forked arm N' to 75 force the inking-roller underneath the stamping-die I, while with the reverse movement of the head B its movement will be communicated to swing the inking-roller outwardly across the ink-pad R, from which it receives 80 a fresh supply of ink.

The operation of my device is as follows: The material to be printed upon is first placed upon the bed A, the printing-head B being then in its raised position, with the inking- 85 roller K underneath the die I. With the downward movement of the head B the inking-roller is swung outwardly across the pad R, and the bed A is drawn inwardly underneath the head B and die I until it engages 90 a stop V in the rear of the machine underneath the inking-pad R, the head B being permitted to continue its downward movement by reason of the springs F, interposed between the head and the upper ends of the 95 rack-bars F'. The continued downward movement of the head after the bed A is brought in contact with the stop V brings the die I into forcible contact with the material upon the bed A, the springs J permitting the die-plate to yield sufficiently to reduce the strain. With the return or upward movement of the head the bed-plate is again moved forwardly 100 to the position to which it is shown in Fig. 2,

and the inking-roller K is swung downwardly from the pad R into contact with the under surface of the die I. When the parts are in this position, the printed or stamped material 5 may be removed from the bed A and fresh material substituted, whereupon the operation of the machine is repeated, as above described.

Having thus described my invention, what 10 I claim as new, and desire to secure by Letters Patent, is—

1. The combination of a vertically-reciprocating printing-head; a die connected therewith; a horizontally-reciprocating bed-plate; 15 a stop for limiting the inward movement of the bed-plate; and connections whereby said bed-plate is adapted to be actuated from the printing-head.

2. The combination of a vertically-reciprocating printing-head; a die connected therewith; a horizontally-reciprocating bed-plate; a stop for limiting the inward movement of the bed-plate; and connections whereby said bed-plate is adapted to be actuated from the 25 printing-head, said connections being provided with a yielding element adapted to per-

mit the printing-head to continue its movement to a limited extent, after the bed-plate is in engagement with said stop.

3. The combination of a vertically-reciprocating printing-head; a die yieldingly connected therewith; a horizontally-reciprocating bed-plate; a stop for limiting the inward movement of the bed-plate; and connections whereby said bed-plate is adapted to be actuated from the printing-head. 30

4. The combination of a vertically-reciprocating printing-head; a die connected therewith; a horizontally-reciprocating bed-plate; a stop for limiting the inward movement of 40 the bed-plate; connections whereby said bed-plate is adapted to be actuated from the printing-head; and an inking - roller connected with, and actuated from, said head, and adapted to be swung alternately into, and out of, 45 contact with the surface of said die.

In testimony whereof I affix my signature in the presence of two witnesses.

MAX E. BIERACH.
